(57) **CLAIM**

The ornamental design of a hard floor cleaning tool, as shown and described.

DESCRIPTION

FIG. 1 is a front top right perspective view of a hard floor cleaning tool, showing the new design;

FIG. 2 is a front top left perspective view thereof;

FIG. 3 is a rear top right perspective view thereof;

FIG. 4 is a rear top left perspective view thereof;

FIG. 5 is a front bottom left perspective view thereof;

FIG. 6 is a front bottom right perspective view thereof;

FIG. 7 is a rear bottom left perspective view thereof;

FIG. 8 is a rear bottom right perspective view thereof;

FIG. 9 is a top view thereof;

FIG. 10 is a bottom view thereof;

FIG. 11 is a right side view thereof;

FIG. 12 is a left side view thereof;

FIG. 13 is a front view thereof; and,

FIG. 14 is a rear view thereof.

The broken lines in the figures show portions of the hard floor cleaning tool that form no part of the claimed design.
